UNITED STATES PATENT OFFICE.

BERNHARD M. BESKOW, OF CLEARWATER, FLORIDA.

HAIR WAVER OR CRIMPER.

Application filed July 30, 1926. Serial No. 125,963.

This invention relates to a hair waver or crimper and has for its object to provide a device for this purpose which is simple in construction, so that it may be produced at little cost, and which will be convenient and efficient in use.

The invention in its preferred form is made from a single piece of spring sheet steel or other resilient material and comprises a series or plurality of staggered or intermeshing fingers extending from a spring body part consisting of separated portions which may be compressed towards each other to separate said fingers in crossed position, for the insertion of dampened hair between said fingers, so that when the pressure of the thumb and fingers of the user on the said separated body portions is released the fingers will spring into waving or crimping positions, holding the hair between them. Thus by the nipping action of the spring-held fingers the waver or crimper will be retained in the hair, with the fingers in waving or crimping positions, until released or pulled out.

In the accompanying drawing Fig. 1 is a plan view of one form of the invention. Fig. 2 is an edge view of the same with the intermeshing fingers in normal position. Fig. 3 is a view similar to Fig. 2 with the separated body portions compressed to bring the fingers into position to receive the hair. Fig. 4 is a cross section through the fingers when holding the hair for waving or crimping. Figs. 5 and 6 illustrate, in plan and side views, a simple modified form of the invention.

Referring to the drawing, 12 denotes the body part of the preferred form of the invention and which body part consists of two separated portions of thin spring sheet metal integral with each of which are staggered or intermeshing fingers 13 normally held in the position, as shown in Fig. 2, by the resilience of the body portions 12. In other words, the body part 12 is so tensioned as to cause the intermeshing fingers to spring towards each other so as normally to cross or intermesh, as shown in Figs. 2 and 6. The fingers 13 are preferably of curved or concavo-convex form in cross section, as clearly shown in Fig. 4, the alternating fingers being reversely curved. To bring the fingers 13 into position for inserting the waver or crimper into the hair, or for placing the hair in the waver or crimper, the separated por-

tions of the body 12 are forced towards each other, as shown in Fig. 3, by compression between the thumb and fingers of the user; and as soon as the pressure is relaxed, after the fingers 13 are engaged with the hair *a*, they will spring into positions for holding the hair in waving or crimping position between them. (See Fig. 4.) It will be understood that the waver or crimper may comprise a greater or lesser number of fingers 13 than are shown in Fig. 1.

In the modified form of the invention shown in Figs. 5 and 6, the crimper preferably consists of a single piece of spring wire bent to form outside connected members 15 and an intermediate member 16 which may be jointed by solder, at 17, to the outside members where they come together at one end of the crimper. The free end of the member 16 normally springs upward in contact with the adjacent end of the crimper which said free end of said member 16 slightly overlaps. The member 16 comprises the humped-up portion 18 which may be pressed upon by the thumb of the user to force said member 16 into the position shown in dotted lines in Fig. 6, to enable the hair which is to be crimped to be wound around it; and when the pressure is released the member 16 will spring back towards the body members 15 and hold the hair in crimping or waving position.

Having thus described my invention I claim and desire to secure by Letters Patent:—

1. A hair waver or crimper comprising two sets of intermeshing spring members alternating with and normally springing towards each other, and adapted to be forced, by pressure, into hair-engaging position, said members being staggered or disposed in different planes so that the members of one set will be between the members of the other set.

2. A hair waver or crimper consisting of a single piece of spring sheet material comprising a body part having separated portions integral with each of which is a set of waving or crimping fingers normally springing towards and intermeshing with each other, and which may be forced into hair-engaging positions by compression on said separated portions of said body part, the fingers of one set being between the fingers of the other set.

3. A hair waver or crimper consisting of

a single piece of spring sheet material comprising a body part having separated portions integral with each of which are waving or crimping fingers normally springing towards and intermeshing with each other, and which may be forced into hair-engaging positions by compression on said separated

portions of said body part, the fingers of one set being between the fingers of the other set, said fingers being curved or of concavo-convex form in cross section. 10

In testimony whereof I affix my signature.

BERNHARD M. BESKOW.
